H. J. BAKER

CONCRETE FORM

Filed Jan. 19, 1923

Patented Jan. 20, 1925.

UNITED STATES PATENT OFFICE.

HUGH J. BAKER, OF INDIANAPOLIS, INDIANA.

CONCRETE FORM.

Application filed January 19, 1923. Serial No. 613,565.

To all whom it may concern:

Be it known that I, HUGH J. BAKER, a citizen of the United States, residing at Indianapolis, in the county of Marion and State of Indiana, have invented a new and useful Concrete Form, of which the following is a specification.

It is the object of my invention to provide an effective device of simple and inexpensive construction for supporting and spacing the falsework tiles for, and the reinforcing rods of, a reinforced concrete floor, and for permitting the ready removal of such tiles; and for providing at the same time a convenient and strong attaching device for the attachment of desired articles to the ceiling, such for instance as metal lathing or wiring conduits.

In carrying out my invention, I provide a metal spacing and supporting member which rests on the falsework soffit, preferably with its ends depending at the edges of the soffit, to position such member on the soffit and to provide hooks for supporting the metal tiles, and which has an elevated central portion over the middle of the soffit for supporting in proper spaced relationship the reinforcing rods embedded in the concrete beam; which elevated central portion is eventually embedded in the concrete so that the end portions of the member will be supported therefrom after the soffit and tiles have been removed; and these end portions of the member are provided with suitable holes, in any suitable number, for the attachment thereto of any desired thing which is to be supported from the ceiling, such as the aforesaid metal lathing or wiring conduits.

The accompanying drawing illustrates my invention: Fig. 1 is a fragmentary perspective view showing two soffits and the metal tiles between them and part of the concrete in place, with the reinforcing rods and tile properly supported and positioned by supporting and spacing members of my invention; Fig. 2 is a perspective view of one of said supporting and spacing members, before association with the reinforcing rods; Fig. 3 is a fragmentary transverse section through the lower part of the beam of a ceiling, showing my supporting and spacing member partially embedded therein and partially depending therefrom in its condition after the removal of the soffit and

tiles; and Fig. 4 is a fragmentary perspective view showing a modification.

I use my invention in connection with any well-known style of falsework, having the usual soffits 10, conveniently wooden planks, and any suitable tiles or forms 11 between the soffits of the falsework, the tiles being shown as sheet-metal sections of standard construction, which abut in the assembled falsework and which each extend from one soffit to the next, as is clear from Fig. 1, though forms of any material may be used; and in connection with any usual reinforcing rods 12 located for eventual embedment in the beams 13 of the concrete floor 14 which is poured upon the falsework formed by such soffits and tiles. As my invention does not concern itself with the support for the soffits, or with the girders ordinarily provided at the ends of the beams 13, I have not illustrated those things.

According to my invention, I support the reinforcing rods 12 in proper position, and also preferably support the tiles 11, by special supporting and spacing members 20 of which the preferred form is shown in perspective in Fig. 2. There may be any number of these supporting and spacing members, arranged along each soffit 10. They should be spaced apart not farther than the length of a tile section 11, so that one may be located at each joint between abutting tile sections, as is clear from Fig. 1. I preferably make this supporting and spacing member of a single piece of sheet-metal, though it is not essential that it be either of sheet metal or in a single piece.

This reinforcing and spacing member in this preferred form comprises two end parts 20 which project down at the edges of the soffit 10 and lie against such edges, which end portions 20 at their ends are bent upward to form hooks 21 for receiving the lower edges of the tile sections 11, preferably at the joints between such tile sections: two intermediate horizontal parts 22 which project toward each other from the upper ends of the hooked end portions 20 and lie upon the upper surface of the soffit 10 near its two edges; two upstanding leg portions 23 which project upward from the face of the soffit 10 from the adjacent ends of the two intermediate horizontal parts 22; and a central portion 24 connecting the upper ends of the two leg portions 23. The central portion 24

24 is thus elevated above the upper surface of the soffit 10, so that concrete may flow beneath it for embedding it in the beam 13. This central portion 24 forms a support for the reinforcing rods 12. To hold such reinforcing rods in proper position, the central part 24 is preferably provided near each end with an upwardly projecting finger 25, and at a greater distance from each end with a shorter upstanding finger 26. Each reinforcing rod 12 is held in proper position between the fingers 25 and 26 near one end of the central portion 24; and when such reinforcing rods 12 are in place the fingers 25 and 26 may if desired be bent around them to hold them rigidly in place, as is clear from Figs. 1 and 3. The fingers 25 and 26 before being thus bent are shown in Fig. 2. The fingers 25 and 26 are preferably formed by partly cutting out suitable strips in the central portion 24, and bending such partly cut-out strips upward, as is clear from Fig. 2; so that such fingers are integral with the remainder of the supporting and spacing member. This serves further to make the central member 24 narrower, because the fingers 25 are strips from the edges of such central member 24; and to provide a hole through the middle of said central member 24, because the fingers 26 are punched out of such middle part; which hole and cut-away edge parts make it easier for the concrete to flow beneath the central portion 24 and fill the space there without voids; so that the strength of the beam 13 will not be interfered with, and the embedment of the parts 23 and 24 of my spacing and supporting member in the concrete will be more secure. Sometimes the bent-down end portions 20 and their hooks 21 may be omitted, or the ends 30 may be turned up to serve as non-supporting spacers for tiles or forms as indicated in Fig. 4, as when other supporting arrangements for the tiles or forms 11 are used.

45 I make my spacing and supporting members in the form shown in Fig. 2, and place them in proper positions on the soffits 10. Then I place the tile sections 11 in the hooks 21 if they are so to be supported, as that gives a firm support for such tile members and lets them lie sufficiently close against the edges of the soffits 10 so that there will not be sufficient space at such edges for any loss of concrete therethrough. Where desired, 50 any spreaders for the tiles may be used, but to avoid confusion these are not shown as they are no part of my invention. Then the reinforcing rods 12 are put in place on my spacing and supporting members, in the 55 positions determined by the fingers 25 and 26, and preferably fastened there by bending such fingers over them as shown in Fig. 1. Then the concrete is poured for the beams 13 and floor 14. When the concrete has sufficiently set, the falsework is removed. The

soffits 10 may be taken away, and then the ends of each spacer are pulled downward and toward each other, as by gripping them with suitable pliers, thus moving them from the dotted-line to the full-line position 70 shown in Fig. 3 and straightening out if desired the bends between the parts 20, 22, and 23. By thus pulling down the end portions, they are released from the tile sections 11, which may be stripped off the concrete in 75 any usual or convenient manner. In the same way, the parts 30, 22, and 23 may be pulled down, after the tiles or forms are removed.

The central portion 24 and leg portions 80 23 of my supporting and spacing member is now embedded in the lower part of the beam 13, and is very firmly attached to the reinforcing rods 12 therein; but the more or less straightened parts 22 and 20 or 22 85 and 30 are now projecting downward from the lower surface of such beam 13, as is indicated in full lines in Fig. 3. If these downwardly projecting parts are not desired, they can readily be cut off, partly or 90 wholly, as by suitable shears or by a cold chisel. However, they furnish excellent attaching members, because of their firm support from the beam 13 and reinforcing rods 12, and may be used for the attachment to 95 the ceiling of anything desired, such as metal lathing or wiring conduits. To facilitate this attachment of other things, I preferably provide the portions of my reinforcing and spacing member which will 100 eventually project downward from the beam 13 with suitable holes, which may be in any desired arrangement and location and of any desired number. As shown, I have provided one such hole in each of the parts 105 20 and 22, or 30 and 22, which arrangement and number of holes ordinarily is sufficient; but this arrangement and number of holes is merely illustrative.

I have shown my supporting and spacing member as being made of a single stamping of sheet-metal, and I prefer to make it of sheet metal and as a single stamping. However, this is merely a preferable way of making it, and my invention is not limited to 115 sheet metal or to the single-stamping structure save in those claims where that is specified.

I claim as my invention:

1. A supporting and spacing member for 120 use in concrete floors, comprising a portion adapted to rest on the upper surface of a soffit, two hooked depending end portions for receiving the edges of tile sections and hanging below said part which rests on the soffit, and an elevated portion raised 125 above and supported from the part which rests on the soffit so that it will be embedded in the concrete beam when the latter is poured.

2. A supporting and spacing member for use in concrete floors, comprising a portion adapted to rest on the upper surface of a soffit, two hooked depending end portions for receiving the edges of tile sections, and an elevated portion supported from the part which rests on the soffit so that it will be embedded in the concrete beam when the latter is poured, those parts of said member which are not embedded in the concrete when the latter is poured including a part provided with an opening through it to permit the attachment thereto of things to be attached to the ceiling. 70
- 15 3. A supporting and spacing member for use in concrete floors, comprising a portion adapted to rest on the upper surface of a soffit, two hooked depending end portions for receiving the edges of tile sections and hanging below said part which rests on the soffit, and an elevated portion raised above and supported from the parts which rest on the soffit and arranged to support reinforcing rods of the concrete beam to be formed on the soffit. 80
- 30 4. A supporting and spacing member for use in concrete floors, comprising a portion adapted to rest on the upper surface of a soffit, two depending parts for extending downward at the edges of the soffit, and an elevated portion supported from the parts which rest on the soffit and arranged to support reinforcing rods of the concrete beam to be formed on the soffit. 85
- 35 5. A supporting and spacing member for use in concrete floors, comprising a portion adapted to rest on the upper surface of a soffit, two depending parts for extending downward at the edges of the soffit, and an elevated portion supported from the parts which rest on the soffit and arranged to support reinforcing rods of the concrete beam to be formed on the soffit, said elevated portion being provided with upwardly projecting fingers for locating the reinforcing rods which rest on said elevated portion. 90
- 50 6. A supporting and spacing member for use in concrete floors, comprising a portion adapted to rest on the upper surface of a soffit, and an elevated portion supported from the parts which rest on the soffit and arranged to support reinforcing rods of the concrete beam to be formed on the soffit, said elevated portion being provided with upwardly projecting fingers for locating the reinforcing rods which rest on said elevated portion. 100
- 55 7. A supporting and spacing member for use in concrete floors, comprising a portion adapted to rest on the upper surface of a soffit, and an elevated portion supported from the parts which rest on the soffit and arranged to support reinforcing rods of the concrete beam to be formed on the soffit, 115
- 60 8. A supporting and spacing member for use in concrete floors, comprising a portion adapted to rest on the upper surface of a soffit, and two hooked depending end portions for receiving the edges of tile sections, said member being provided with upwardly projecting fingers for locating the reinforcing rods which rest on said elevated portion. 120
- 65 9. A supporting and spacing member for use in concrete floors, comprising a portion adapted to rest on the upper surface of a soffit, and two hooked depending end portions for receiving the edges of tile sections, said member being provided with upwardly projecting fingers for locating the reinforcing rods which rest on said elevated portion. 125
10. A supporting and spacing member for use in concrete floors, comprising two end portions for projecting downward at the edges of a soffit, two intermediate portions projecting toward each other from the upper ends of said end portions and arranged to rest on the upper surface of a soffit near its edges, upstanding legs from the adjacent ends of said intermediate portions, and a central elevated portion supported on said upstanding legs for embedment in the concrete. 130
11. A supporting and spacing member for use in concrete floors, comprising two end portions for projecting downward at the edges of a soffit, two intermediate portions projecting toward each other from the upper ends of said end portions and arranged to rest on the upper surface of a soffit near its edges, upstanding legs from the adjacent ends of said intermediate portions, and a central elevated portion supported on said upstanding legs for embedment in the concrete, all said parts being formed of a single strip of sheet metal. 135
12. A supporting and spacing member for use in concrete floors, comprising two end portions for projecting downward at the edges of a soffit, two intermediate portions projecting toward each other from the upper ends of said end portions and arranged to rest on the upper surface of a soffit near its edges, upstanding legs from the adjacent ends of said intermediate portions, and a central elevated portion supported on said upstanding legs for embedment in the concrete, said end portions being provided with upwardly opening hooks for receiving the lower edges of tile sections. 140
13. A supporting and spacing member for use in concrete floors, comprising two

- end portions for projecting downward at the edges of a soffit, two intermediate portions projecting toward each other from the upper ends of said end portions and arranged to rest on the upper surface of a soffit near its edges, upstanding legs from the adjacent ends of said intermediate portions, and a central elevated portion supported on said upstanding legs for embed-
ment in the concrete, said central elevated portion being provided with fingers for po-
sitioning on said elevated portion reinforcing rods for embedment in the concrete.
14. A supporting and spacing member for use in concrete floors, comprising two end portions for projecting downward at the edges of a soffit, two intermediate portions projecting toward each other from the upper ends of said end portions and ar-
ranged to rest on the upper surface of a soffit near its edges, upstanding legs from the adjacent ends of said intermediate portions, and a central elevated portion supported on said upstanding legs for embed-
ment in the concrete, said end portions be-
ing provided with upwardly opening hooks for receiving the lower edges of tile sec-

tions, and said central elevated portion be-
ing provided with fingers for positioning on said elevated portion reinforcing rods 30 for embedment in the concrete.

15. A supporting and spacing member for use in concrete floors, comprising two end portions for projecting downward at the edges of a soffit, two intermediate portions 35 projecting toward each other from the upper ends of said end portions and arranged to rest on the upper surface of a soffit near its edges, upstanding legs from the adjacent ends of said intermediate portions, and a central elevated portion supported on said upstanding legs for embedment in the concrete, those parts of said member which are not embedded in the concrete when the lat-
ter is poured including a part provided 40 with an opening through it to permit the attachment thereto of things to be attached to the ceiling.

In witness whereof, I have hereunto set my hand at Indianapolis, Indiana, this 50 day of January, A. D. one thousand nine hundred and twenty-three.

HUGH J. BAKER.
